and Co. ATTORNEY

ATTORNEY

WITNESS:

UNITED STATES PATENT OFFICE

MONROE BRITTAINE, OF CHICKASHA, OKLAHOMA

LOCOMOTIVE OIL BURNER

Application filed April 17, 1931. Serial No. 520,937.

My present invention has reference to improvements in oil burners and is particularly designed for heating the boilers of locomotives.

5 An object of the invention is the provision of an oil burner for locomotive fire boxes which is simple, durable, effective and reliable, which may be sustained in the firebox without liability of vibration and which will 10 thoroughly mix oil, air and steam in the spray plate or nozzle and direct flame from the said plate or nozzle in fan-shaped formation as well as at vertical angles from said plate on to the walls of the fire box.

15 A further object is the provision of an oil burner in which the oil is caused to circulate through and be heated in its passage through pipes to render the same volatile at its point of delivery to the spray plate or nozzle, and 20 to cause a mixture of steam and hot air under pressure to be ejected onto the spray plate for directing the vaporized fuel therefrom around the firebox.

To the attainment of the foregoing the invention also consists in certain other advantages as well as in details of construction which will be hereinafter described, illustrated by the drawing and pointed out with 25 particularity in the appended claims.

30 In the drawing:

Figure 1 is a top plan view of a burner in accordance with this invention.

Figure 2 is a substantially vertical longitudinal sectional view therethrough.

35 Figure 3 is a front elevation thereof.

Except for the spray plate my improved oil burner is made up of pipe sections and couplings for said sections.

40 Referring now to the drawing in detail, the numeral 1 designates a horizontally arranged pipe that comprises a plurality of short pipe sections connected together by a plug and by couplings as will hereinafter be described. The pipe 1 has screwed on one 45 of its ends a T-coupling 3 and in this coupling there is screwed a plug 2. The plug has centrally screwed therethrough a steam conducting tube 4 which, of course, enters the pipe 1. The steam tube is connected to a suitable source of steam supply and, while

not shown by the drawing, the tube has its passage controlled by a hand operated valve.

There is screwed in the lateral branch of the T-coupling 3 an oil inlet pipe 6, the said pipe being connected with a suitable source of oil supply and the oil from the supply may be heated.

55 Screwed in two of the confronting pipe sections 1 there is a cross coupling 7 and in one of the pipe sections connected with the coupling there is screwed one end of a plug 5. The tube 4 is threaded and screwed centrally through the plug 5 so that the tube is not in contact with the inner wall of the sections comprising the pipe 1.

60 The plug 5 affords a stop for oil which enters the pipe 1 to direct such oil through the lateral or transverse branches of the cross coupling 7, but the oil before passing through such branches will be heated by the steam conducting tube 4. The lateral branches of the T-coupling 7 have screwed therein oppositely directed outwardly extending pipes 8 on

65 whose outer ends there are couplings for short and downwardly directed pipes 9. 70 Horizontally arranged pipes 10 are screwed in the couplings and thus connected with the short pipes 9. The pipes 10 are of the same length and have screwed on their outer ends

75 couplings to connect with the pipes 10 upstanding pipes 11. The upstanding pipes 11 have screwed on their upper ends couplings in which there are screwed inwardly extending short pipes 12 and these pipes 12 have 80 their confronting ends screwed in a cross coupling 13. The top or outwardly extending branch of the coupling 13 is closed by a plug 14 while the depending branch has 85 screwed therein a short depending pipe 15.

90 The lower end of the pipe 15 is screwed in a T-coupling 16, and the lower end of the T-coupling 16 is closed by a screw plug 19, the same being screwed in and closing the upstanding branch of a coupling 18'. The coupling 18' is connected to the outer end 95 of the pipe 1, and likewise is connected to a pipe extension 20 which is in reality an extension of the said pipe 1. The outer and threaded end of the pipe 20 is screwed in a round and threaded opening 23 on the inner 100

end of a burner spray plate 21. The spray plate has its bottom gradually widened from its said end 23 to its outer and open end and the sides are formed with upstanding flanges 5 22, while the rear and top of the plate 21 is formed with a downwardly arched lip 24 that enters the burner plate between the sides 22 thereof.

In the outstanding or lateral branch of the 10 coupling 16 there is screwed a pipe 17 and this pipe has screwed on its outer end a C-coupling to which is connected a depending oil outlet or nozzle pipe 18.

The plug 5 and the section of the pipe 1 15 adjacent thereto are connected together by a T-coupling 25 and in the lateral branch of this coupling there is screwed a pipe 25'. The pipe 25' is connected with a source of hot air and while not shown by the drawing, the 20 said pipe 25' has its passage controlled by a valve.

The device is positioned within a fire box or the like, and in operation, the oil passing through a part of the pipe 1 is heated by the 25 hot steam conducting pipe 4 so that the oil, while still in a heated state will pass through the pipes 9, 10, 11, 15, 17, and the nozzle or outlet pipe 18, the said oil, of course, being delivered onto the burner plate 21. Hot air from the pipe 25' may be directed to the pipe 1 and its extension 20 to mix with the oil in the pan 21 to mix and further heat the oil in the pan. The oil is ignited and when the flame has reached a sufficient temperature 30 a full flow of hot air and a full flow of steam is directed into the pan so that the burning vapor in the pan will be spread against the sides and end of the fire box. The heat thus created will be imparted to the oil 35 conductor pipes so that after the fire is first started the oil will be delivered in a vaporized form onto the burner pan 21. Obviously the flow of oil as well as the flow of hot air and steam is regulated in the air passage 40 to the burner plate and pan.

Obviously I do not wish to be restricted to the precise details herein shown and described, therefore, hold myself entitled to make such changes therefrom as fairly fall 45 within the scope of what I claim.

Having described the invention, I claim:

An oil burner comprising a horizontally 50 extending pipe having one end plugged and an outwardly flared burner plate having side flanges thereon connected to its other end, said plate having a downwardly extending lip partially closing the open end of the pipe, a second plug within the pipe spaced from 55 said first plug, a steam pipe extending in spaced relation within said pipe, and through said plugs and terminating beyond said second plug, an oil pipe communicating with said first pipe adjacent said first plug, laterally extending pipes connected to the first 60 named pipe, one on each side, between said 65

plugs and adjacent said second plug, said lateral pipes having downward extensions which merge into horizontal pipes extending parallel to the first named pipe, upstanding pipes connecting said horizontal pipes with 70 inwardly directed sections terminating in a coupling directly above the first named pipe, a pipe closed at its lower end depending from the coupling and having a branch extending outwardly and then downwardly terminating 75 in a nozzle immediately above said plate, and an air pipe connected to the first named pipe intermediate the second plug and the end of the steam pipe.

In testimony whereof I affix my signature. 80
MONROE BRITTAINE.
